CARTON SEALING MACHINE

William A. Joplin, Wollaston, Mass., assignor to
Pneumatic Scale Corporation, Limited, Quincy,
Mass., a corporation of Massachusetts

Application April 21, 1937, Serial No. 138,209

9 Claims. (Cl. 93—6)

This invention relates to a carton sealing machine and more particularly to a machine for producing a sealed carton having a tearing strip interposed between certain of the top flaps thereof.

The invention has for an object to provide a novel and improved construction of carton sealing machine for producing a sealed carton having a tearing tab of the character specified in a novel, 10 efficient and economical manner.

With this general object in view and such others as may hereinafter appear, the invention consists in the carton sealing machine and in the various structures, arrangements and combinations of 15 parts hereinafter described and particularly defined in the claims at the end of this specification.

In the drawings illustrating the preferred embodiment of the invention, Fig. 1 is a side elevation of the carton sealing machine; Fig. 2 is a 20 plan of the same; Fig. 3 is a sectional view taken on the line 3—3 of Fig. 2; Fig. 4 is a detail illustrating the mechanism for the application of the sealing tab, to be referred to; Fig. 5 is a sectional detail of a portion of the adhesive applying mechanism; and Fig. 6 is a perspective view of the partially sealed carton.

In general, the present invention contemplates a carton sealing machine in which provision is made for introducing a tearing tab which may 30 comprise a strong flexible strip of fabric or the like between certain of the top flaps of the sealed carton during the sealing thereof, in such a manner as to leave a portion of the strip projecting slightly beyond the carton to form a tab which 35 may be conveniently grasped in order to tear open the carton. The sealing machine finds particular use in the production of a carton of the type having pouring holes formed in the underlying wider top flap, and wherein the tearing tab also functions to seal the pouring openings and to extend 40 across the carton to permit a portion of the underlying wider top flap of the sealed carton to be torn away to thereby expose the pouring openings.

In the preferred embodiment of the invention, 45 the top sealing machine herein illustrated is particularly adapted to be used for sealing the top flaps of a carton as above described. Such a carton is illustrated in Fig. 6 and comprises a body portion 12 provided with end flaps 18, 20 and side flaps 26, 28. As herein shown, the end flaps 18, 20 are of such a length as to permit the openings 19 provided in the side flap 26 to communicate with the material in the carton when the uppermost flap is torn away. The tearing strip 25 is applied to the carton over the pouring openings

with a short tab 21 extending beyond the carton to serve as a handle when in use. The remaining flap 28 is folded down and adhesively sealed on top of the tearing strip so that in the completely sealed carton the tearing strip is inserted between the two side flaps 26, 28. For the purpose of facilitating the removal of the top flap so as to expose the openings 19, the uppermost flap 28 is provided with a weakened line such as a scored line or a line of perforations 23 which in the completed carton is positioned in alignment with the inner edge of the tearing strip so that when in use only the portion of the upper flap corresponding to the width of the tearing strip is removed to expose the pouring openings.

Referring now to the drawings, the invention is illustrated as embodied in a top sealing machine which in general may comprise the machine forming the subject matter of the United States Patent to Scales, No. 930,090, dated August 3, 1909, to 20 which reference may be had for a complete description thereof. For the purposes of the present invention only sufficient portions of the complete top sealing machine have been herein illustrated and will be described as will enable the invention to be understood. In general, the machine illustrated in the drawings comprises a belt 10 for conveying the cartons 12 from the filling mechanism or other point from which the filled cartons are to be supplied. The cartons are arranged to enter the machine, one at a time, in timed relation to the operating mechanism by the usual pusher arm 14 which releases the foremost carton in the line into the machine. The carton is now advanced to a position where it is engaged by one of a series of carrier arms 16 mounted on a horizontally moving endless chain 17.

As shown in Figs. 1 and 2, the cartons are successively moved through the machine past the various mechanisms for folding down the two 40 end flaps, applying adhesive to the flaps, folding down one of the side flaps, applying a tearing strip, and, for thereafter closing the remaining flap down upon the tearing strip and upon the top of the carton, as will be described.

As herein illustrated, the usual apparatus for tucking in the end flaps 18, 20 comprises a stationary curved and flared rail 22, positioned in the path of movement of the carton and a rotary tucker 24 which folds down the end flap 20 and 50 follows along with the carton to tuck the flap under the rail 22. The carton, with its side flaps 26, 28 horizontally extended and with the end flaps folded down is now advanced to the gluing device, generally indicated at 30, where adhesive 55

is applied to the top of the extended flaps 26, 28 by a pair of glue rolls 32. At the same time, a strip of adhesive is applied to the underside of the flap 26 by a yieldingly mounted roll 34 which normally is urged against the upper roll 32, to receive the adhesive, before the carton passes through. The roll 34 is carried by an arm 36, pivoted at 38 and having its outer end 40, urged upwardly toward the roll 32 by a spring 42.

As shown in Fig. 5, the lower roll 34 applies a narrow strip of glue along the inner edge of the flap 26 and forms the surface against which the tearing strip 25 is applied when the flap is folded down on top of the carton. The upper glue roll 32 receives adhesive in the usual manner from a spreading roll 44 running in a glue pot 46.

As herein shown, the carton is supported at its lower end upon a horizontal track 48 on which it travels and after passing the adhesive applying station 30, the flap 26 is folded over upon the top of the package by a curved rail 50 and thereafter arrives at the tearing strip applying station, generally indicated at 52, which will now be described.

As illustrated in detail in Fig. 3, the tearing strip applying device is provided with mechanism for feeding a strip of material of a character difficult to tear, such as fabric, reenforced paper, or the like, from a roll and for cutting off a predetermined length of the strip to be applied to the carton. As herein shown, the roll of material 54 is supported above the mechanism upon a vertical rod 56 mounted in a bracket 58. The strip is guided around a vertical rod 60 and over idler rolls 62, 64, and between guides 66, 68. The strip is given a one quarter twist between the rod 60 and roll 62. The strip guides 66, 68 are arranged at an angle of 45 degrees with respect to the top of the carton to facilitate the application of the strip to the carton, as will be described. The strip applying device is supported from the machine frame 8 in brackets 67 and the strip of material is intermittently fed through the guides 66, 68, by a feed roll 70 in cooperation with a yieldingly mounted idler roll 72. The feed roll 70 is mounted upon a shaft 74 supported in brackets 75 and is arranged to be rotated through connections from a cam shaft 76 also mounted in brackets 75. As herein shown, a cam 78 cooperates with a cam roll 80 carried by an arm 82 pivoted on a cross shaft 84. The arm 82 is connected by a rod 86 to a lever 88 carried in an arm 90, loosely mounted on the shaft 74. The lever 88 is provided with a holder 92 which carries a fibre plug 94. The fibre plug 94 is arranged to frictionally engage the periphery of a disk 96 which is formed integrally with the feed roll 70.

In operation, when the cam 78 raises the arm 82 a cramping action results between the fibre plug 94 and the disk 96 thereby causing the feed roll to be rotated in the manner of a ratchet feed. On the return stroke of the arm 90, the fibre plug slides along the periphery of the disk 96 without causing any movement of the feed roll. An arm 98, extended from the arm 90 carries a stop pin 100 against which the arm 88 rests on its down or return stroke. A spring 102 urges the cam roll 80 against its cam 78.

From the description thus far it will be observed that a predetermined length of the strip is fed into position to be cut off preparatory to being applied to the carton. As herein shown, the cut-off knife 104 slidably mounted in a cross bracket 106 is arranged to cooperate with a stationary shearing edge 108 forming a part of the lower

guide bar 68. The knife 104 is arranged to be intermittently reciprocated by connections from a closed cam 110 fixed to the cam shaft 76 and as herein shown, these connections comprise a cam roll 112, carried on an arm 114 which is fixed to a rocker shaft 116 and a second arm 118 fixed to the rocker shaft, connected to the knife 104 by a rod 120.

As will be observed from inspection of Fig. 3, the strip 25 is fed into a position extending into the path of the oncoming carton and during the operation of the machine, the strip is cut off just prior to the arrival of the carton. Upon the carton coming in contact with the extended end of the strip, it is pressed down on top of the carton by a stationary applying roll 120 which is mounted in an extension 122 from the bracket 75. It will be seen that in the operation of the machine the strip 25 is initially grasped between the bite of the roll 120 and the corner of the oncoming carton and upon continued movement of the carton the strip is pulled from the guides 66, 68 and applied to the carton.

Provision is made for preventing the operation of the strip feeding mechanism when the supply of incoming cartons is depleted and to this end, a feeler finger 130 normally urged into the path of the cartons is arranged to lift a latch 132 when engaged by a carton, to permit the arm 82 to operate. If a carton is not at hand, the latch 132 will engage an extension 134 on the end of the arm 82 and thereby render the feeding mechanism inoperative. As herein shown, the feeler 130 is mounted on a shaft 136, supported in bearings 138, 140 which are secured to the carton side guides 141. An arm 142, also secured to the shaft 136 is connected by a rod 143 to one arm 144 of a bell crank, the other arm forming the latch 132. A spring 146 normally urges the finger 130 into the path of the cartons.

After leaving the strip applying device, the remaining flap 28 is folded down over the strip in any usual or preferred manner, as by the curved rails 150, 152 whereupon the carton is ejected from the machine into the usual pressure device 154 for setting the glued flaps.

The driving apparatus for the machine may in general comprise the apparatus shown in the Scales patent above referred to and as herein diagrammatically illustrated, see Figs. 1 and 2, 50 may include a pulley 160, driven in any usual or preferred manner, which is connected to the glue roll shaft 162 by cooperating gears 164, 166. The spreader roll shaft 168 is driven from the shaft 162 through the gears 170, 172. The outer 55 end of the glue roll shaft is provided with a sprocket 174 which is connected by a chain 176 to a sprocket 178. The sprocket 178 is fast on the end of a cross shaft 180 and is also provided with a bevel gear 182 which in cooperation with 60 a bevel gear 184 serves to drive the carrier chain 17. The cam shaft 76 is driven from the shaft 180 by sprockets 186, 188 and chain 190. Provision is made for rotating the tucker arm 24 and, 65 as herein shown, a sprocket 192 fast on the cam shaft 76 is connected by a chain 194 to a sprocket 196 fast on the tucker shaft 198. The chain 194 is guided over the rocker shaft 116 by an idler sprocket 200.

While the preferred embodiment of the invention has been herein illustrated and described, it will be understood that the invention may be embodied in other forms within the scope of the following claims.

Having thus described the invention, what is claimed is:

1. In a carton sealing machine, in combination, carton supporting mechanism, mechanism for folding down the top flaps of the carton, cutting means for forming an individual tearing strip from a roll supply thereof and means for introducing the individual tearing strip thus formed between some of said top flaps with 10 an end thereof projecting beyond the carton.
2. In a carton sealing machine, in combination, carton supporting mechanism, means for folding down the narrower top flaps of the carton, means for then folding down one of the wider top flaps of the carton, means for adhesively affixing a tearing strip to the upper surface of said wider of said top flaps, and means for thereafter folding down and adhesively affixing the remaining top flap upon the tearing 20 strip.
3. In a carton sealing machine, in combination, carton supporting mechanism, means for folding in the narrower top flaps of the carton, means for applying adhesive to both surfaces of 25 one of the wider top flaps of the carton, means for folding down said wider top flap to adhesively affix it to the previously folded narrower flap, means for applying a tearing strip to the upper surface of said wider top flap to adhesively affix the same thereto, and means for thereafter 30 folding down the remaining top flap.
4. In a carton sealing machine, in combination, carton feeding mechanism for conveying successive cartons through the machine, means for folding in the narrower top flaps, means for applying adhesive during the traverse of the 35 carton through the machine to both the surfaces of one of the wider top flaps, and to one surface of the remaining top flap, means for then folding down the first mentioned wider top flap, strip feeding mechanism for feeding a tearing strip into a position where one end projects beyond the carton and the strip is laid down upon the adhesive surface of said folded down wider top 40 flap, and means for thereafter folding the remaining top flap to complete the closing of the carton.
5. In a carton sealing machine, in combination, carton conveying mechanism, means for folding down one of the wider top flaps, means for applying adhesive to the upper surface thereof, means for feeding a tearing strip into a position to be engaged by the forward edge of the upper surface of the carton, means for applying 45 said tearing strip to the upper surface of said previously folded down wider top flap, and means for thereafter folding down the remaining top flap to complete the closing of the carton.
6. In a carton sealing machine, in combination, carton conveying mechanism, means for folding down one of the wider top flaps, means for applying adhesive to the upper surface thereof, means for feeding a tearing strip into a position to be engaged by the forward edge of the upper surface of the carton, means for applying 50 said tearing strip to the upper surface of said previously folded down wider top flap including a roll adapted to roll said tearing strip onto the upper surface of the carton as the carton traverses beneath the same, and means for thereafter folding the remaining top flap to complete the closing of the carton.
7. In a carton sealing machine, in combination, carton conveying mechanism, folding means for folding in the narrower top flaps of the carton, means for applying adhesive to the upper surface of one of the wider top flaps of the carton, means for folding the same into operative carton closing position, strip feeding mechanism for feeding a tearing strip from a supply 55 thereof into a position to be engaged by the carton, mechanism for severing the strip to form an individual tearing strip, mechanism for applying the individual tearing strip to the surface of the folded down wider top flap, and mechanism for thereafter folding down the remaining top flap to complete the closing of the carton.
8. In a carton sealing machine, in combination, means for conveying a supply of cartons into the machine, means for folding down the top flaps of the carton, strip feeding mechanism for feeding a tearing strip into a position to be interposed between some of the top flaps of the carton during the folding thereof, cutting means for forming an individual tearing strip 60 prior to its complete application to the carton and control mechanism for discontinuing the operation of the strip feed in the event of the absence of a carton.
9. In a carton sealing machine, in combination, carton conveying mechanism, means for successively folding some of the top flaps of the carton, cutting means for forming an individual tearing strip from a supply thereof and strip feeding mechanism operative to interpose the individual tearing strip thus formed between 65 some of the flaps of the carton and between the folding of successive flaps.

WILLIAM A. JOPLIN. 55
